CLAIM

(21) Appl. No.: **29/529,602**

The ornamental design for a combined motor housing and water tank for hair straightening apparatus, as shown and described.

(22) Filed: **Jun. 9, 2015**

DESCRIPTION

(30) **Foreign Application Priority Data**

Dec. 9, 2014 (EM) 002593491-0003

FIG. 1 is an isometric view of an embodiment of a combined motor housing and water tank for hair straightening apparatus showing my new design.

(51) **LOC (10) Cl.** **28-03**

FIG. 2 is a right side elevational view of the combined motor housing and water tank for hair straightening apparatus of FIG. 1.

(52) **U.S. Cl.**

FIG. 3 is a left side elevational view of the combined motor housing and water tank for hair straightening apparatus of FIG. 1.

USPC **D28/38; D28/73**

FIG. 4 is a front elevational view of the combined motor housing and water tank for hair straightening apparatus of FIG. 1.

(58) **Field of Classification Search**

FIG. 5 is a rear elevational view of the combined motor housing and water tank for hair straightening apparatus of FIG. 1.

USPC D28/35, 37-38, 10, 73

FIG. 6 is a top view of the combined motor housing and water tank for hair straightening apparatus of FIG. 1; and,

CPC A45D 1/00-1/28; A45D 2/00-2/001;

FIG. 7 is a bottom view of the combined motor housing and water tank for hair straightening apparatus of FIG. 1.

A45D 2002/006; A45D 2002/007; A45D

The broken lines and the unshaded areas within the broken lines illustrate portions of the article and form no part of the claimed design.
